UNITED STATES PATENT OFFICE.

EDWARD B. ALLEN, OF BRIDGEPORT, CONNECTICUT, ASSIGNOR TO THE SINGER
MANUFACTURING COMPANY, A CORPORATION OF NEW JERSEY.

WORK-HOLDER FOR BUTTONHOLE-SEWING MACHINES.

1,240,642.

Specification of Letters Patent. Patented Sept. 18, 1917.

Application filed April 29, 1912. Serial No. 693,778.

To all whom it may concern:

Be it known that I, EDWARD B. ALLEN, a citizen of the United States, residing at Bridgeport, in the county of Fairfield and 5 State of Connecticut, have invented certain new and useful Improvements in Work-Holders for Buttonhole-Sewing Machines, of which the following is a specification, reference being had therein to the accompanying drawings.

This invention relates to a special construction for the work-holder of a button-hole sewing machine and means for operating the same. It has for its objects to provide effective means for opening and closing the clamping members; to maintain the work clamped in the holder for the least possible time requisite for the cutting and stitching operations, so as to insure against needless loss of time in the shifting and adjusting of the work between consecutive stitching operations; to provide means for the relative adjustment of the opposed clamping jaws; to provide means of adjustment for the lift of the upper clamping jaws for fabrics of different thicknesses; to provide simple and effective means for spreading apart the separable pairs of opposed clamping jaws, and actuating means therefor; to facilitate the removal of one or both of the separable parts of the work-holder to provide access to the parts of the mechanism beneath the same; and to otherwise improve the work-holder in its construction and actuating means.

In its preferable embodiment, the present improvement is applied to a buttonhole stitching machine of the type represented in my United States Patent No. 1,024,490, dated April 30, 1912. The work-holder comprises a traveling slide-plate connected with and deriving operative movements from the feeding mechanism and provided at one end with spaced notches in which are confined by means of a pivotally mounted locking lever fulcrumed thereon headed pivotal studs depending from two independent clamp-plates resting upon said slide-plate and drawn together with their adjacent 45 edges in abutting relation by means of springs.

Upon each clamp-plate at the end opposite its depending stud is secured for transverse adjustment thereon a bearing bracket upon which is fulcrumed a tilting block having secured thereon for endwise adjustment a clamping lever carrying a foot constituting one of the clamping jaws opposed to a jaw afforded by the clamp-plate. A spring interposed between the clamp- 60 plate and said clamping lever forces the latter upwardly to retract the upper clamping jaw. Mounted upon said bearing bracket is a controlling cam adapted to force said lever down upon the work and provided 65 with a lateral arm having an upwardly extending cam-shaped end portion.

A clamp-closing rock-lever is fulcrumed upon the carrying member of one of the slit-cutting elements with one arm operatively connected with another member carrying the other of the slit-cutting elements, while an oppositely extending arm of said rock-lever, in the advance movement of the traveling slit-cutting device, first engages and depresses the cam-shaped end portion of the controlling-cam lever-arm and subsequently engages the same intermediate its ends for a second and final stage of the clamp-closing action, the second stage occurring as the slit-cutting elements approach each other in a cutting operation.

The unclamping of the work is effected by engagement with a second lateral arm connected with the controlling cam by a 85 tappet-arm depending from a reciprocating rod connected with and actuated by the vibrating controlling lever of the stop-motion device in arresting the operation of the stitch-forming mechanism.

Upon the work-holder slide-plate intermediate the adjacent edges of the independently pivoted clamp-plates is journaled a rotary cam-button having rigidly connected therewith a lateral arm to which is applied 95 a spring for normally maintaining the cam-button in unspredding position. The engagement of said lateral arm by a reciprocating bar connected with and actuated by the traveling support for the slit-cutting 100 mechanism acts to turn the cam-button into spreading position wherein it is held by a

spring-pressed latch-lever engaging said lateral arm. The retraction of said latch-lever by engagement of a thread-cutter actuating bar deriving operative movements from a 5 connection with the feeding mechanism permits the cam-button to return to initial unspreading position under the action of its spring.

In the accompanying drawings, Figure 1 10 is a side elevation and Fig. 2 a plan of the forward portion of a buttonhole sewing machine below the bracket-arm, and embodying the present invention. Fig. 3 is a bottom plan of the same with the base partially in section. Fig. 4 is a sectional side 15 elevation and Fig. 5 a rear end view of that portion of the machine provided with the stop-motion. Fig. 6 is a front elevation, partly in section, showing a portion of the 20 frame, the slide-plates sustaining the work-holder, and the looper mechanism. Fig. 7 is a perspective view of a portion of the work-clamp, and Fig. 8 a similar view of one of the lower clamp-plates. Fig. 9 is an 25 edge view, partly in section, of the work-holder, and Fig. 10 a perspective view of one of the controlling cams for the clamping levers. Figs. 11, 12 and 13 are perspective views representing portions of the clamp-spreading device.

As represented in the drawings, the frame of the machine is constructed with the hollow rectangular base 1 having a suitably apertured top forming the bed-plate 2 from the rear end of which rises the hollow standard 3 of the bracket-arm. The base is shown provided with the removable section 4 for access to the looper mechanism at the front. Suitably journaled in the base is the longitudinally extending main-shaft 5 formed with quartering cranks 6 embraced by the lower ends of pitman-rods 7 by means of which it is connected with the upper needle-actuating shaft.

45 Journaled in the lower portion of the standard 3 is the transverse cutter-shaft 8 provided upon its front end with a loose grooved belt-wheel 9 adapted to be connected by a belt with the source of power independently of the main-shaft 5. Between the hub 10 of the belt-wheel 9 and the disk 11 fixed upon the shaft 8 is a clutch device controlled by means of the flange 12 of the controlling lever 13 fulcrumed at 14 and pressed normally into clutch-disengaging position by means of the spring 15 interposed between the flange 12 and the boss 16 of the bed-plate 2.

60 The cutter mechanism is shown and described more fully in my application Serial No. 593,784, filed Nov. 23, 1910. It comprises the traveling fulcrum-plate 17 having its opposite edges fitted within suitable guideways 18 of the bed-plate and provided 65 with the spaced upwardly projecting lugs

19 sustaining the transverse fulcrum-pin 20. Mounted upon the fulcrum-pin 20 are the upper and lower cutter-levers 21 and 22, the upper lever carrying at its forward end the primary cutter-member 23, and the lower in 70 practice carrying an opposed coöperating cutter-member.

The rearward ends of the cutter-levers are drawn together by means of a spring 24 which maintains the downwardly offset end 75 portion 22* of the lower lever 22 in contact with the lower side of the cylindrical collar 25 fixed upon the cutter-shaft 8, and the lower edge of the upper cutter upon the periphery of the actuating cam 26 fixed 80 upon the cutter-shaft. The cam 26 is formed to produce upon the upper cutter-lever a two-stage operative movement to give the opposed cutting members successively a rapid closing movement and a 85 greatly retarded work-engaging or cutting movement.

The cutter-shaft 8 has fixed thereon the disk 27 formed with a cam-groove 28 entered by the lateral stud 29 of a link 30 having its enlarged rearward end portion 30* yoked to embrace the cutter-shaft 8 and its forward end apertured to receive the stud-bolt 31 projecting laterally from a rearward extension of one of the fulcrum-sustaining 95 lugs 19, whereby the fulcrum-plate and the cutter-levers fulcrumed thereon are given traveling movements toward and from stitching position preparatory and subsequent to each slit-cutting operation.

100 The top of the bed-plate 2 is formed with lateral guiding grooves 32 entered by inwardly projecting ribs 33 upon the longitudinally extending bars 34 connected at their rearward ends by the plate 35 to form the 105 main slide-frame of the work-holder. The bars 34 are provided with depending apertured lugs 36 in which is sustained the transverse rod 37 having slidably fitted thereon the apertured lugs 38 depending from the 110 bottom of the cross slide-plate 39 resting upon the bed-plate with its notched rearward edges fitted to the correspondingly notched confining blocks 40 secured upon the member 35 by means of screws 41.

115 At its forward extremity, the slide-plate 39 is formed with the spaced notches or open-ended slots 42 which are entered by the shanks 43 of studs having heads 44 and depending from near the forward and inner edges of the swinging clamp-plates 45 and 46 which are formed in their adjacent edges with the complementary notches 47 forming an elongated aperture embracing the paths of movement of the needle and the upper cutting member, the upper faces of these clamp-plates being roughened at 48 to afford the lower clamping jaws. Fulcrumed upon the lower face of the slide-plate 39 by means of the screw-stud 49 is the curved "locking 120

lever 50 formed in its rearward edge with spaced notches 51 adapted to embrace the heads 44 of the studs 43 to lock them within the notches 42 of the slide-plate. The lever 50 has an additional notch 52 entered by the shank of a clamp-screw 53 tapped into the slide-plate 39 by means of which the locking lever may be firmly secured in operative position.

10 Each of the clamp-plates is provided at its rearward end with a stud 54 adapted to enter an aperture in a detachable finger-plate 55 to which is connected one end of a spring 56 having its opposite end attached 15 to a stud 57 sustained by the slide-plate 39.

The clamp-plates 45 and 46 are thus normally drawn together to maintain them in operative relation for the cutting and stitching of a buttonhole, but by disengaging the finger-plate 55 from the stud 54 and removing the spring 56, either slide-plate may be swung outwardly upon its pivotal stud 43, as represented in Fig. 2, for access to the lower stitch-forming mechanism, the slide-plate 39 being cut out centrally at 39^x to permit such inspection and to provide clearance for the operative parts.

The slide-plate opening 39^x is obviously sufficiently wide to provide easy access to the looper mechanism beneath, and as represented in the drawings has a width somewhat exceeding that of the space occupied by the loopers. The top of the slide-plate 39 affords an unobstructed space adjacent 35 the clamp-plates of such extent as to permit their free outward movement, as represented in Fig. 2, to substantially uncover the opening 39^x, so that the whole of such opening is effective for access to the loopers in threading or adjusting or otherwise manipulating the same. The simple expedient employed for exposing the loop-takers for such purposes greatly facilitates the use of the machine in practical operation.

45 Each of the clamp-plates 45 and 46 is shown provided in its upper face near the rearward end with a transverse groove 58 entered by the depending tongue 59 of the foot 60 of a bearing bracket formed with a slot 61 to receive the shank of a fastening screw 62 by means of which it is secured for lateral adjustment upon the clamp-plate. Rising from the foot 60 of the bearing bracket are the spaced parallel forwardly extending arms 63 near the bases of which is sustained the transverse fulcrum-pin 64 upon which is secured by means of the set-screw 65 the tilting block 66 formed upon its upper face with the tongue 66^x.

50 Upon the upper face of the block 66 is secured by means of the screw 67 a spring clamping lever comprising the superposed members 68 and 69, the former of which is notched near its forward end to receive the latter so as to afford a clamping jaw in

relatively yielding forward and rearward sections. Both of the lever-members 68 and 69 are formed in their rearward portions with elongated apertures to receive the shank of the screw 67, and the member 69 70 has in its lower face a groove 69^x to receive the tongue 66^x upon the block 66, thereby providing for the longitudinal adjustment of the upper clamping elements.

Journalized in lugs 63^x of the arms 63 is the transverse rock-shaft 70 upon which is fixed intermediate such arms the clamp-lever controlling cam 71 formed upon one side with the cam-rib 72 and upon the opposite side with the laterally projecting finger 73. 80 The cam-rib 72 is adapted for engagement with the inclined upper face of a wedge-shaped wear-plate 74 formed with the slot 75 in its rearward portion to embrace the shank of the screw 67 by means of which 85 it is adjustably clamped upon the top of the upper clamp-plate 68, a washer 76 being interposed between the head of the screw 67 and said wear-plate. By adjusting the position of the wear-plate lengthwise of the 90 clamping lever the clamping pressure of the latter upon the work may be determined and the work-holder may be adjusted for different thicknesses of material. The clamping lever is normally pressed upward, 95 whereby the wear-plate 74 is maintained continuously in operative relation with the cam 71, by means of the spring 77 interposed between the bottom of the lower lever member 69 and the top of the clamp-plate 45. 100

Fixed upon the rearward end of the rock-shaft 70 sustained by the clamp-plate 45 is a rearwardly extending cam-arm 78 formed in its rearward portion with the upwardly extending cam-shaped projection 79. Upon 105 the lower cutter-lever 22 is disposed the fulcrum-stud 80 upon which is mounted a clamp-closing rock-lever formed with a rearwardly extending arm 81 having a slot 82 which embraces a screw-stud 83 upon the 110 upper cutter-lever 21 and a forwardly extending arm 84 whose depending forward portion 85 is adapted to engage the cam-shaped upper edge of the cam-arm 78. In the advance of the slit-cutting mechanism 115 from retracted position, as represented in Figs. 1 and 2, to cutting position, the studs 80 and 83 carried by the cutter-levers maintain their initial relation, and the rock-lever 81 84 moves bodily forward, thus carrying 120 the rounded nose of the part 85 into operative engagement with the edge of the member 79 of the cam-arm and imparting an initial clamp-closing movement through the action of the cam 71. The rocking of the 125 upper cutter-lever 21 succeeding this traveling movement to perform the slit-cutting operation causes the tilting of the rock-lever 81 84 and engagement of the nose of the part 85 with that part of the cam-arm 78 130

intermediate the part 79 and the supporting rock-shaft, as indicated in Fig. 9, thereby imparting a second stage of turning movement to the rock-shaft 70 and causing the 5 forcible engagement of the cam-rib 72 with the wear-plate 74 to effect the clamping of the work by the clamping lever.

To insure the closing of the clamping levers in unison, the hub of the cam-arm 78 10 is formed with an upwardly extending arm 86 formed with a lateral pin 87 adapted to enter the forked upper extremity 88 of an upwardly extending arm 89 fixed upon the clamp-controlling rock-shaft 70 sustained 15 by the clamp-plate 46. The parts 87 and 88 afford a coupling between the clamp-operating rock-shafts 70 which are readily retracted from operative engagement when the clamp-plates 45 and 46 are separated, as 20 represented in Figs. 1 and 2.

For the manual control of the clamp when desired, the hub 90 of a finger-lever 91 is fixed upon the end of the rock-shaft 70 opposite the cam-arm 78, and this hub is 25 shown formed with a laterally extending lug 92 adapted for engagement with the operative edge of a stopping cam-disk 93 adjustably secured by means of the screw 94 to the forward extremity of the adjacent 30 clamp-bracket arm 63. By suitably adjusting the cam-disk 93 upon the screw 94 as a fulcrum, the degree of lift of the clamp-lever 68 69 may be adjusted for different classes of work.

35 The eccentricity of the cam-rib 72 which acts in performing the final clamping movement is so slight that its engagement with the wear-plate 74 produces no tendency to turn the rock-shaft 70 in the reverse direction to that described, and no other locking 40 means are therefore required to maintain the clamp closed during the stitching operation. The reverse movement of the controlling cam 71 for unclamping the work is effected by the engagement with its lateral 45 finger or arm 73 of a tappet arm 95 secured upon and depending from a reciprocating rod 96 having its forward end journaled in the apertured head 97 of a stud 98 secured 50 in the lower end of the head 99 of the bracket-arm, and having its flattened and apertured rearward end 96^x pivotally connected by means of the pin 100 with one end of a link 101 whose opposite end is connected 55 by means of the pin 102 with the upwardly extending arm 103 of an angle-lever mounted upon a fulcrum-stud 104 upon the rearward end of the machine base and provided with a rearwardly extending 60 arm 105.

65 The angle-lever arm 105 rests upon a lug 106 extending laterally from a plunger-block 107 fitted within a cavity therefor in the swinging stop-motion controlling lever 65 108 which is provided with the boss 109

pivotedly mounted by means of the fulcrum-pin 110 between the bearing lugs 111 at the rear of the base 1. The plunger-block 107 is normally pressed downwardly by means of the spring 112 interposed between the 70 upper end of a socket therefor in the swinging lever 108 and said block, and has a tooth 107^x adapted to engage the periphery of the stopping cam 113 which in practice carries one of the operative elements of the 75 clutch comprising the disk 114 whose hub 115 is fixed upon the main-shaft 5 upon which is loosely mounted the belt-wheel 116 formed with a lateral cavity to receive the clutch-disk 114.

80 The tilting of the stop-motion lever 108 to laterally withdraw the tooth 107^x from the peripheral notch 113^x of the cam 113 causes the clutch to establish driving relation between the continuously rotating pulley 116 and the main-shaft through the fixed disk 114, and the return of the stop-motion lever 108 to initial position, as represented in Fig. 4, causes the tooth 107^x to ride up the eccentric edge of the cam until it 90 snaps into the notch 113^x for arrest of the main-shaft. The rise of the block 107 under the action of the stopping cam 113 causes the lifting of the lug 106 whose engagement with the angle-lever arm 105 causes the 95 rocking of the same and the advance of the tappet-arm 95 in opposition to the spring 117 interposed between the same and the head 97 of the stud 98. In its forward 100 movement, the tappet-arm strikes the arm 73 of the clamp-controlling cam 71 and turns the latter for the release of the clamp-arms which rise under the action of their respective springs into the position represented in Fig. 1.

105 The clamp-plates 45 and 46 are provided in their under sides and at their adjacent edges, between the notches 47 and the pivotal studs 43, each with a transverse groove 118 in which is secured by means of screws 119 a hardened contact-block 120 for engagement with the rotary cam-button 121 which is shown formed with straight parallel sides and concentrically curved ends adapted to engage the adjacent extremities of the 110 blocks 120. The cam-button 121 is formed at the upper end of a rocking pin 122 journaled in the slide-plate 39 and having secured upon its lower end the collar 123 with the oppositely projecting arms 124 and 120 125. Secured upon the arm 125 is the laterally extending plate 126 having the eye 127 to which is secured one end of a spring 128 whose opposite end is attached to an eye 129 upon the slide-plate 39 and acts to normally 125 maintain the cam-button in what may be termed "unspreading" position, in which its flat sides are in contact with the ends of the contact-blocks 120 and the adjacent edges of the clamp-plates 45 and 46 are thus per- 130

mitted to come close together under the action of the springs 56.

The outer extremity of the arm 124 lies within the range of movement of the reciprocating cam-block 130 pivotally mounted by means of the stud-screw 131 upon the head 132 of a rack-bar 133 fitted within a suitable slideway in the bed-plate 2 and meshing with a pinion 134 mounted upon a fixed stud 135 and meshing in turn with a series of rack-teeth 136 upon the adjacent edge of the traveling fulcrum-plate 17 of the slit-cutting mechanism. The body of the cam-block 130 has its upper face formed at the outer extremity with a bevel, and a lateral extension 130* thereof has the inner extremity of its upper face oppositely beveled for a purpose to be later described. The cam-block is normally pressed upwardly against the bottom of the slide-plate 39 by means of a spring 137 having one arm secured to the block 132 by means of a screw 138 and another arm resting against the under side of the cam-block.

Journalized upon a stud-screw 139 upon the under face of the slide-plate 39 is a three-armed latch-lever comprising an arm 140 notched in its outer end to form a detaining shoulder 141, a second angularly arranged arm 142 having a lateral finger 143, and a third arm 144 in substantial alignment with the arm 142 and provided with an aperture 145 in which is secured one end of a spring 146 whose opposite end is connected with the stud 147 upon the slide-plate 39. The spring 146 serves to yieldingly maintain the latch-lever in normal position with its arm 142 in contact with the stop-pin 148 upon the slide-plate 39.

When the fulcrum-plate 17 advances for a slit-cutting operation, the rack-bar 133 retreats and carries with it the cam-block 130 the beveled inner extremity of whose extension 130* rides over the end of the spreader-arm 124, thereby deflecting the cam-block from effective engagement with the spreader-arm. In the return of the parts to initial position, the shouldered end of the cam-block extension 130* operatively engages the spreader-arm 124 and thrusts the same forwardly, the arm 125 being thus shifted so as to temporarily deflect the latch-lever arm 140 until its extremity passes the shoulder 141, when the latch-lever under the action of its spring 146 snaps into latching engagement with the arm 125, thereby holding the same and the connected cam-button 121 in clamp-spreading position, as represented in Fig. 2 and in dotted lines in Fig. 11, in which the parts are maintained during the whole of the succeeding stitching operation.

As represented herein, the stitch-forming mechanism comprises a laterally jogging needle 149 mounted in the swinging carrier

150 sustained for rotation in the bracket-arm head 99. Coöperating with the needle beneath the work-holder are the threaded looper 151 and the non-threaded looper 152 and overlying loop-spreader 153, these loop-taking implements being mounted upon the oscillating carrier 154 sustained by a rotary support, and adapted to coöperate with the needle respectively in its depth-stitch and edge-stitch thrusts, as set forth in detail in my United States Patent No. 1,030,046, dated June 18, 1912. In performing its operative movements, the needle descends through the aperture 155 of the needle-throat 156 which is in practice sustained upon a rocking yoke and adapted to be temporarily displaced from normal operative position by the advance of the lower cutting member for a cutting operation.

Secured upon the bottom of the bed-plate 2 by means of screws 157 is a plate 158 carrying a screw-stud 159 upon the top of which is mounted the shank 160 of a thread-trimming knife whose blade 161 has a path of movement upon the fulcrum-stud 159 in a plane between the advance or loop-holding position of the non-threaded looper 152 and spreader 153 and the needle-throat 156, as represented in Fig. 6. The knife-shank 160 is provided with an elongated aperture 162 entered by the head of a screw-pin 163 upon the under side of an endwise movable bar 164 journalized in a suitable guideway in the top of the bed-plate and having at its rearward end an upwardly projecting hollow post 165 carrying an apertured lug 166 in which is secured one end of a spring 167 whose opposite end is attached to a similar lug 168 upon the bracket-arm standard 3. The post 165 has journalized therein upon the screw-stud 169 the roller-stud 170 which is maintained by means of the spring 167 in operative engagement with the pear-shaped controlling cam 171 whose hub 172 is secured by means of the set-screw 173 upon the upright shaft 174 journalized in suitable bearings of the bed-plate and carrying upon its lower end the gear-wheel 175 meshing with the gear-wheel 176 secured upon the hub 177 of the rotary feed-wheel 178.

By the described connection, the trimmer-actuating cam 171 is caused to rotate in unison with the feed-wheel 178. As the greater portion of its periphery is concentric with its axis of rotation, the knife remains stationary during the greater part of the stitching operation, but at the completion of such operation, the eccentric portion engages the roller-stud 170 and thrusts the bar 164 forwardly, thereby causing the blade 161 to pass between the needle-throat 156 and the looper 152 still holding the last formed loop of needle-thread, whereby the thread is severed, after which the bar 164 is retracted by its spring 167 into initial position and the knife-

blade 161 reassumes its retracted position as represented in Fig. 2.

In the advance of the bar 164 for actuation of the trimming knife, its advance extremity 164^x encounters the arm 144 of the latch-lever by means of which it is shifted into the dotted line position of Fig. 3, thereby releasing the arm 125 of the spreading device and permitting the cam-button 121 to assume initial unspredding position whereby the separable pairs of clamping jaws are drawn together by their respective springs.

The cam 179 on the main-shaft has a groove 180 entered by the roller-stud 181 of the lever 182 fulcrumed upon the fixed stud 183 and having a link connection 184 with the clutch-lever 185 journaled concentrically with the feed-wheel and having its hub 186 provided with notches entered by the inner ends of the clutch-dogs 187 slotted to embrace the depending flange 178^x of the feed-cam, the clutch-dogs being maintained yieldingly in operative relation with said flange by means of the arms 188 secured to the hub 186 normally resting against the springs 189 secured to the adjacent edges of the clutch-dogs. By the means just described, the feed-cam derives a step-by-step partial rotation from the main-shaft during the operation of the stitch-forming mechanism.

The cam-wheel 178 is formed in its upper face with the usual feeding cam-groove 190 and side-shift cam-groove 191. The cam-groove 190 is entered by a roller-stud 192 depending from a lever 193 swinging upon the fixed fulcrum 193^x depending from the bed-plate and provided with an upwardly projecting stud 194 entering and engaging the walls of a transverse slot 195 of the work-holder frame-plate 35, whereby longitudinal traveling movements are imparted to the work-holder. The cam-groove 191 is entered by a stud 196 depending from the arm 197 of a rock-lever mounted upon the fixed fulcrum 198 and having at its opposite end the roller-stud 199 entering a longitudinal guideway in the block 200 secured upon the under side of the cross slide-plate 39, by means of which lateral shifting movements are imparted to the work-holder for the stitching of the opposite sides and the ends of the buttonhole.

During the travel of the slide-plate 39 in the stitching of a buttonhole, the spreader parts are locked in the dotted line positions represented in Figs. 3 and 11. To prevent the reengagement of the spreader-arm 124 by the cam-block 130, the extremity of the finger 143 of the latch-lever arm 142 is so positioned as to engage the forward beveled extremity of the body of the cam-block, thereby thrusting it aside in the advance of slide-plate 39 and the spreader parts carried thereby, so as to leave the spreader parts un-

disturbed until the tripping of the latch-lever by the thread-cutting action as before described.

As described in my Patent No. 1,024,490 before mentioned, the arrest of the main-shaft and the consequent interruption of the operative movement of the clutch-dogs 187 causes the assumption of operative relation between the auxiliary feed-pawl 201 and the segmental series of peripheral ratchet-teeth 75 202 upon the feed cam-wheel 178 by means of which the rotation of the cam-wheel is completed at an increased speed, and the operative portion of the trimming knife actuating cam 171 is brought into engagement 80 with the roller-stud 170 for actuation of the trimming knife 161.

By effecting the closing of the work-clamp in two stages as described, the upper clamping feet are first brought down close to the work to enable the operator to accurately gage the position of the buttonhole relative to the clamping members for a final adjustment preparatory to the actual clamping operation which occurs almost simultaneously 90 with but slightly in advance of the actual buttonhole cutting operation. The closing of the clamp during the slit-cutting operation and opening of the same by a connection with the stop-motion at the instant of 95 arrest of the stitch-forming mechanism affords the operator the longest possible period of time for shifting of the work between consecutive cutting and stitching operations, thereby permitting the machine to 100 be run practically continuously in the production of a series of buttonholes in the same article.

The actuation of the clamp-spreader by a connection with the slit-cutting mechanism 105 and early in the retracted movement of the latter also effects a saving of time, in placing the work-holder in readiness for the stitching operation before the slit-cutting mechanism returns to initial retracted position after a slit-cutting operation, as it permits the suitable adjustment of the cam-plate 203 upon the disk 27 to effect an early 110 engagement with the roller 204 carried by the forwardly extending arm 205 of the 115 clutch-lever rock-shaft 110 to set the main-shaft in motion.

While the present improvement is herein shown and described in what is considered its preferable construction and arrangement of parts, it will be readily seen that it is susceptible of very considerable modification in the form and association of its various elements, and that the invention is not therefore limited to the specific embodiment herein disclosed.

Having thus set forth the nature of the invention, what I claim herein is:—

1. In a buttonhole sewing machine, the combination with a shaft, stitch-forming 130

- mechanism deriving operative movements therefrom, a stop-motion comprising a cam upon said shaft and a spring-pressed plunger controlled thereby, and a work-holder constructed with clamping members separable to release and clamp the work and a controlling rock-shaft therefor provided with an arm, of clamp-opening means comprising a rod carrying a tappet-arm adapted for engagement with the clamp rock-shaft arm, and an angle-lever for communicating endwise movements to the tappet-arm carrying rod from said plunger.
2. In a buttonhole sewing machine, the combination with stitch-forming mechanism, slit-cutting mechanism, a rotary shaft from which the stitch-forming mechanism derives operative movements, a stop-motion for controlling the operation of said shaft, and a work-holder having upper and lower clamping members separable to release and clamp the work, of clamp-closing and clamp-opening means, one of which is operatively connected with the slit-cutting mechanism and the other of which is operatively connected with said stop-motion.
3. In a buttonhole sewing machine, the combination with stitch-forming mechanism, slit-cutting mechanism including a cutter-carrying lever and provided with means for confining it permanently to one side of the stitch-forming mechanism, and a traveling work-holder having upper and lower clamping members separable to release and clamp the work, and a controlling rock-shaft for said work-holder mounted to partake of the traveling movements of the same and provided with an arm, of clamp-closing means acting upon said arm of the clamp-controlling rock-shaft and operatively connected with and operated by said cutter-carrying lever to effect the final closing of the work-holder substantially simultaneously with the slit-cutting action.
4. In a buttonhole sewing machine, the combination with slit-cutting mechanism including a traveling carrier sustaining separable cutting elements, and a work-holder having upper and lower clamping members separable to release and clamp the work, and a controlling rock-shaft therefor provided with an arm, of clamp-closing means operatively connected to and partaking of the movements of a member carrying one of said cutting elements and acting successively upon said arm of the clamp-controlling rock-shaft to partially close the clamp during the travel of the cutter-carriage and to complete the closing action during the approach of said cutting elements in the slit-cutting operation.
5. In a buttonhole sewing machine, the combination with slit-cutting mechanism including co-operating cutting elements and a rock-lever carrying one of said cutting ele-
- ments, and a work-holder having upper and lower clamping members separable to release and clamp the work and a controlling rock-shaft therefor provided with an arm, of clamp-closing means acting upon said arm of the clamp-controlling rock-shaft and having a positive connection with and actuated by said rock-lever.
6. In a buttonhole sewing machine, the combination with slit-cutting mechanism including co-operating cutting elements and a rock-lever carrying one of said cutting elements, and a work-holder having upper and lower clamping members separable to release and clamp the work and a controlling rock-shaft therefor provided with an arm, of a clamp-closing rock-lever mounted independently of but connected with the cutter rock-lever and adapted for engagement with the arm of said clamp-controlling rock-shaft.
7. In a buttonhole sewing machine, the combination with slit-cutting mechanism including two cutting elements and sustaining members therefor, one of which is mounted to perform rocking movements relative to the other, and a work-holder having upper and lower clamping members separable to release and clamp the work and a controlling rock-shaft therefor provided with an arm, of a clamp-closing rock-lever fulcrumed upon one of the cutter members and having an operative connection with the other of said cutter members and adapted for engagement with said arm of the clamp-controlling rock-shaft.
8. In a buttonhole sewing machine, the combination with slit-cutting mechanism including a traveling fulcrum-carrier sustaining a fulcrum-pin upon which are mounted two cutter members one of which performs rocking movements relative to the other, and a work-holder having upper and lower clamping members separable to release and clamp the work and a controlling rock-shaft therefor provided with an arm, of a clamp-closing rock-lever fulcrumed upon one of the cutter-members and having an operative connection with the other of said cutter members and adapted for engagement with said arm of the clamp-controlling rock-shaft.
9. In a buttonhole sewing machine, the combination with stitch-forming, feeding and slit-cutting mechanisms, and a work-holder constructed with separable pairs of clamping jaws, of clamp-jaw spreading means connected with and actuated by the slit-cutting mechanism, and unspredding means connected with and actuated by said feeding mechanism.
10. In a buttonhole sewing machine, the combination with a work-holder comprising separable pairs of separable clamping jaws, and slit-cutting mechanism comprising co-operating cutting elements mounted upon a

traveling carrier, of clamp-closing means connected with and actuated by said cutting mechanism for closing the clamping jaws of each pair upon the work preparatory to the 5 coöperative action of said cutting elements upon the work, and means connected with the cutting mechanism independently of said clamp-closing means for spreading apart said pairs of clamping jaws subsequent to 10 said cutting action.

11. In a buttonhole sewing machine, the combination with stitch-forming mechanism, slit-cutting mechanism comprising a traveling carrier and coöperating cutting elements 15 sustained thereby with means for imparting to-and-fro traveling movements to said carrier and cutting movements to the cutting elements, feeding mechanism, and a work-holder constructed with separable pairs of 20 clamping jaws, of spreading means, an operative connection between said carrier and the spreading means whereby the latter is actuated to separate said pairs of clamping jaws, and unspredding means connected with and 25 deriving operative movements from said feeding mechanism.

12. In a buttonhole sewing machine, the combination with stitch-forming mechanism, a work-holder constructed with separable 30 pairs of clamping jaws, and thread-cutting mechanism including a cutting blade operating beneath the work-holder, of clamp-jaw spreading means, and unspredding means actuated by said thread-cutting mechanism 35 and adapted to cause the approach of said pairs of clamping jaws toward each other substantially simultaneously with the severing of the thread.

13. In a buttonhole sewing machine, the 40 combination with stitch-forming and slit-cutting mechanisms, a work-holder constructed with separable pairs of clamping jaws, and thread-cutting mechanism including a cutting blade operating beneath the 45 work-holder, of clamp-jaw spreading means connected with and actuated by the slit-cutting mechanism, and unspredding means actuated by said thread-cutting mechanism.

14. In a buttonhole sewing machine, the 50 combination with a work-holder constructed with laterally separable pairs of opposed clamping members connected for lateral movement in unison, of spreading means including a rotary controlling member whereby 55 said pairs of clamping members may be separated and drawn together, and actuating means for imparting operative movements to said rotary controlling member.

15. In a buttonhole sewing machine, the 60 combination with a work-holder constructed with laterally separable pairs of opposed upper and lower clamping members, of a rotary cam-button interposed between and in engagement with the lower clamping

members, means for turning said cam-button 65 in opposite directions to effect the spreading and unspredding of the clamping members, and means for yieldingly maintaining said lower clamping members in operative relation with the cam-button. 70

16. In a buttonhole sewing machine, the combination with a work-holder constructed with edgewise separable clamp-plates, clamping levers pivotally mounted thereon and carrying clamp-jaws coöperating with said clamp-plates in gripping the work, yieldingly acting means for forcing said clamp-plates together, and a traveling slide-plate upon which said clamp-plates are mounted, of a rotary cam-button journaled in said 75 slide-plate between and in operative relation with said clamp-plates and adapted to control their spacing apart, and means for turning said cam-button. 80

17. In a buttonhole sewing machine, the 85 combination with a work-holder constructed with edgewise separable clamp-plates, and clamping levers mounted thereon, of a rotary controlling member for forcing said clamp-plates apart, a lateral arm connected 90 with said controlling member, and means applied to said arm for turning it in opposite directions in spreading and unspredding the work-holder.

18. In a buttonhole sewing machine, the 95 combination with a work-holder constructed with edgewise separable clamp-plates, clamping levers mounted thereon, and yieldingly acting means for forcing said clamp-plates together, of a rotary cam-button for forcing 100 said clamp-plates apart, a lateral arm connected with said cam-button, and means applied to said arm for turning it in opposite directions in spreading and unspredding the work-holder. 105

19. In a buttonhole sewing machine, the combination with a work-holder constructed with edgewise separable clamp-plates, and clamping levers mounted thereon, of a rotary cam-button for forcing said clamp-plates apart, spring-actuated means for yieldingly maintaining said cam-button in 110 one extreme position, means acting in opposition to said spring for shifting said cam-button into the other extreme position, a latch device for maintaining said cam-button in the last-named position, and means for tripping said latch device to permit the button to return to its first-named position. 115

20. In a buttonhole sewing machine, the 120 combination with stitch-forming, feeding and slit-cutting mechanisms, and a work-holder constructed with edgewise separable clamp-plates, clamping levers mounted thereon, and yieldingly acting means for forcing 125 said clamp-plates together, of a rotary cam-button interposed between the adjacent edges of said clamp-plates and adapted to

- force them apart, a lateral arm rigidly connected with said cam-button, a spring connected with said arm for maintaining the cam-button in unspredding position, a reciprocating bar connected with the slit-cutting mechanism and acting upon said lateral arm to shift the cam-button into spreading position, a spring-pressed latch applied to said arm for locking the cam-button in spreading position, and a reciprocating bar connected with said feeding mechanism and acting upon said latch to disengage the same from said arm to permit the cam-button to assume unspredding position under the action of its spring. 65
21. In a buttonhole sewing machine, a work-holder comprising a clamp-plate, a bearing bracket, means for securing said bracket for transverse adjustment upon the clamp-plate, a tilting block fulcrumed upon said bearing bracket, a clamping lever, and means for securing said clamping lever upon the tilting block adjustably in a direction transverse to that of said bearing bracket. 70
22. In a buttonhole sewing machine, a work-holder comprising a clamp-plate, a clamping lever mounted thereon, a controlling cam for said clamping lever, a lateral stop member rigidly connected with said controlling cam, and an adjustable stop adapted for engagement with said stopping member to determine through said cam the initial elevated position of said lever. 75
23. In a buttonhole sewing machine, the combination with stitch-forming mechanism including a reciprocating needle-bar carrying a needle and coöperating loop-taking means, and a support disposed in a plane intermediate said needle-bar and the loop-taking means and formed with an opening above and affording access to said loop-taking means of a work-holder comprising edgewise separable clamp-plates mounted above said opening and normally closing the same and pivotally mounted for independent edgewise movement at points near their adjacent edges, and means whereby said clamp-plates are normally drawn together while permitting them to be separated to expose a substantial portion of said opening for access to the looper mechanism. 80
24. In a buttonhole sewing machine, the combination with stitch-forming mechanism including a needle and coöperating loop-taking means, of a work-holder comprising laterally separable clamp-plates, a traveling slide-plate disposed above said loop-taking means and formed with an opening for access thereto, said slide-plate affording a support for said clamp-plates normally covering said opening and presenting an unobstructed bearing therefor adjacent the outer edges of the same to permit the separation thereof a distance com- 85
- mensurate with the width of the space occupied by the looper mechanism, and detachable means for yieldingly drawing said clamp-plates toward each other. 90
25. In a buttonhole sewing machine, the combination with stitch-forming and feeding mechanisms, of a traveling slide-plate connected with said feeding mechanism, and a work-holder comprising clamp-plates each having a clamping lever mounted thereon and secured upon said slide-plate for movement toward and from each other by means of independent pivotal connections including retractable locking means adapted to permit the detachment of said clamp-plates from the slide-plate. 95
26. In a buttonhole sewing machine, the combination with stitch-forming and feeding mechanisms, of a traveling slide-plate connected with said feeding mechanism, and a work-holder comprising clamp-plates each having a clamping lever mounted thereon and secured upon said slide-plate by independent detachable pin-and-slot connections. 100
27. In a buttonhole sewing machine, the combination with stitch-forming and feeding mechanisms, of a traveling slide-plate connected with said feeding mechanism and provided at one end with spaced notches and with a pivotally mounted locking lever, and a work-holder comprising clamp-plates each having a clamping lever mounted thereon and a depending headed stud adapted to enter its respective notch in the slide-plate wherein it is confined by said locking lever. 105
28. In a buttonhole sewing machine, a work-holder comprising edgewise separable clamp-plates, clamping levers mounted upon said clamp-plates, controlling cams for said clamping levers, lateral arms rigidly connected with said controlling cams and formed with detachable interlocking connections, and means applied to one of said cams whereby both of said clamping levers are operated. 110
29. In a buttonhole sewing machine, a work-holder comprising edgewise separable clamp-plates, clamping levers mounted upon said clamp-plates, controlling cams for said clamping levers, a lateral arm rigidly connected with one of said cams and formed with a finger substantially parallel with the axis of motion of said clamping lever, a lateral arm rigidly connected with the other of said cams and formed with a fork normally embracing said finger, and means applied to one of said cams whereby both of said clamping levers are operated. 115
30. In a buttonhole sewing machine, the combination with stitch-forming and feeding mechanisms, of a traveling slide-plate connected with said feeding mechanism, edgewise separable clamp-plates mounted 120
- 125

upon and sustained by said slide-plate and pivotally connected therewith at one end, bearing brackets secured in said clamp-plates at their opposite ends, clamping 5 levers pivotally mounted in said brackets, controlling cams mounted in said brackets and adapted to operate said clamping levers, lateral arms rigidly connected with said cams and detachably connected together for 10 movement in unison, and means applied to one of said cams whereby both clamping levers are simultaneously operated.

31. In a buttonhole sewing machine, the combination with a work-holder constructed 15 with laterally separable pairs of opposed upper and lower clamping members, clamp-opening and -closing means, and a button-hole cutting device, of means independent of said clamp-opening and -closing means 20 and operatively connected with said cutting device to receive operative movements derived from the lateral movements of the cutting device relatively to said work-holder, whereby said pairs of clamping members 25 may be separated to spread the work.

32. A buttonhole sewing machine, having, in combination, stitch-forming mechanism and a non-rotary work-holding clamp, mechanism for actuating the stitch-forming 30 mechanism and relatively moving the stitch-forming mechanism and the work-holding clamp to sew about a buttonhole, an independently actuated cutter, and connections between the cutter and clamp for closing the 35 clamp by movement of the cutter toward the face of the work.

33. A buttonhole sewing machine, having, in combination, stitch-forming mechanism and a work-holding clamp, mechanism for 40 actuating the stitch-forming mechanism and relatively moving it and the work-holding clamp to sew about a buttonhole, a cutter, a cutter-carrying lever, mechanism actuating the lever to move the cutter toward and from 45 the material, and connections between said lever and clamp for closing the clamp by movement of the lever toward the material.

34. A buttonhole sewing machine having, in combination, stitch-forming mechanism 50 and a work-holding clamp, mechanism for actuating the stitch-forming mechanism and relatively moving it and the work-holding clamp to sew about a buttonhole, a cutter comprising coöperating cutting elements, a 55 lever carrying one of said cutting elements, mechanism for actuating the lever to move said cutting element toward and from the material, and means for establishing operative connection between said lever and the 60 work-clamp whereby the latter is closed upon the material.

35. A buttonhole sewing machine, having, in combination, stitch-forming mechanism, a work-holding clamp, mechanism for actu-

ating the stitch-forming mechanism and 65 relatively moving the stitch-forming mechanism and the work-holding clamp to sew about a buttonhole, a cutter, connections between the cutter and clamp for closing the clamp by the cutting movement of the cutter, and means timed in its action by a connection with a moving member of the machine for automatically opening the clamp after the completion of the sewing. 70

36. A buttonhole sewing machine having, 75 in combination, stitch-forming mechanism and a work-holding clamp, mechanism for actuating the stitch-forming mechanism and relatively moving the stitch-forming mechanism and the work-holding clamp to sew 80 about a buttonhole, a cutting device permanently positioned at one and the same side of the stitch-forming mechanism and mounted independently of the work-holding clamp and actuated independently of the stitch- 85 forming mechanism, and connections between the cutting device and the clamp for closing the clamp by movement of the cutter toward the face of the work.

37. In a buttonhole sewing machine, the 90 combination with a work-holder having upper and lower clamping members separable to admit the work, and slit-cutting mechanism comprising a cutting element and a carrier upon which the same is mounted, of 95 an operative connection between said carrier and the work-holder and controlled by the carrier whereby the work-holder is closed in the movement of the cutting element toward the plane of the operative faces of said 100 clamping members.

38. In a buttonhole sewing machine, in combination, stitch-forming mechanism, a work-holder having upper and lower clamping members separable to admit the work, 105 a controlling rock-shaft therefor provided with an arm, slit-cutting mechanism comprising a cutter-carrying member movable laterally toward and from the stitch-forming mechanism in performing an operative 110 cycle, and means connected with said arm of the clamp-controlling rock-shaft and operatively connected with and operated by said member of the cutting mechanism to effect the final closing of the work-holder substantially simultaneously with the slit-cutting action. 115

39. In a buttonhole sewing machine, in combination, a work-holder having upper and lower clamping members separable to 120 admit the work, a controlling rock-shaft therefor provided with an arm, slit-cutting mechanism comprising a cutting element, a pivotally mounted carrier therefor, and actuating means for said carrier and means independent of said actuating means for establishing operative connection between said arm of the clamp-controlling rock-shaft and 125

said carrier for effecting the final closing of the work-holder substantially simultaneously with the slit-cutting action.

40. In a buttonhole sewing machine, in combination, a work-holder having upper and lower clamping members separable to admit the work, a controlling rock-shaft therefor provided with an arm, slit-cutting mechanism comprising a cutting element, a 10 carrier therefor, a fulcrum for said carrier mounted substantially parallel with said controlling rock-shaft, actuating means for said carrier, and means independent of said actuating means for establishing operative connection between said arm of the clamp-controlling rock-shaft and said carrier for effecting the final closing of the work-holder substantially simultaneously with the slit-cutting action.
- 15 41. In a buttonhole sewing machine, in combination, stitch-forming mechanism, a work-holder having upper and lower clamp-

ing members separable to admit the work, a controlling rock-shaft therefor provided with an arm, slit-cutting mechanism comprising a reciprocating carrier, a cutting element mounted thereon and movable toward and from the stitch-forming mechanism and said clamping members, actuating means for said carrier, and means independent of said actuating means for establishing operative connection between said arm of the clamp-controlling rock-shaft and said carrier for effecting the final closing of the work-holder substantially simultaneously with the slit- 35 cutting action.

In testimony whereof, I have signed my name to this specification, in the presence of two subscribing witnesses.

EDWARD B. ALLEN.

Copies of this patent may be obtained for five cents each, by addressing the "Commissioner of Patents, Washington, D. C."

It is hereby certified that in Letters Patent No. 1,240,642, granted September 18, 1917, upon the application of Edward B. Allen, of Bridgeport, Connecticut, for an improvement in "Work-Holders for Buttonhole-Sewing Machines," an error appears in the printed specification requiring correction as follows: Page 10, line 109, claim 38, strike out the word "laterally"; and that the said Letters Patent should be read with this correction therein that the same may conform to the record of the case in the Patent Office.

Signed and sealed this 20th day of November, A. D., 1917.

[SEAL.]

R. F. WHITEHEAD,

Acting Commissioner of Patents.
